(57) **CLAIM**

I claim the ornamental design for an adhesive tape for body attachment, as shown and described.

DESCRIPTION

FIG. 1 is perspective view of an adhesive tape for body attachment, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a reference view showing a configuration of use. The broken lines shown in the drawings depict environmental features which do not form a part of the claimed design.
